VACUUM FUEL FEED DEVICE

Frederik Barfod, South Bend, Ind., assignor to
Bendix Products Corporation, South Bend, Ind.,
a corporation of Indiana

Application January 9, 1935, Serial No. 1,035

2 Claims. (Cl. 103—236)

This invention relates to carburetors and more particularly to carburetors of the fuel lift type, which draw fuel from a supply tank positioned at a lower level than the fuel nozzle of the carburetor. This application represents improvements in the carburetor disclosed in Milton E. Chandler Patent 2,051,820, issued August 25, 1936.

An object of this invention is to provide an improved carbureting device which will lift fuel from the supply tank to a chamber positioned above the fuel nozzle of the carburetor, and supply the carburetor with fuel at constant pressure.

A further object is to provide an improved carbureting unit of simplified construction which will eliminate the fuel pump or vacuum tank ordinarily used therewith.

A still further object is to provide an improved fuel lift carburetor of simplified construction, which may be economically manufactured and will be economical and positive in operation.

Other objects and advantages of the invention will be apparent from the following detailed description, and from the illustrative embodiments of the invention in the accompanying drawings, which are submitted merely for purposes of illustration, and are not intended to define the scope of the invention, reference being had for that purpose to the appended claims.

In the drawings wherein similar reference characters refer to similar parts throughout the several views:

Figure 1 is a vertical section illustrating a preferred embodiment of the invention;

Figure 2 is a sectional view taken on line 2—2 of Figure 1;

Figure 3 is a sectional view taken on the line 3—3 of Figure 1;

Figure 4 is a sectional view taken on the line 4—4 of Figure 1;

Figure 5 is an enlarged sectional view of the suction venturi;

Figure 6 is an enlarged sectional view of a suction valve;

Figure 7 is an enlarged sectional view showing a modified arrangement of the suction venturi and pressure responsive valve; and

Figure 8 is a diagrammatic view showing the fuel passages disclosed in Figures 1 to 5.

Referring more particularly to the drawings, there is shown a carbureting unit having an upper or airhorn section 10, a middle or body section 12 and a throttle body section 14. The upper and middle body sections are preferably formed of zinc or similar material suitable for die-casting, while the throttle body section is preferably a sand casting. An air cleaner 13, of known construction, is fixed to airhorn 10 in the usual relation. The induction passage formed by airhorn 10 divides at section 12 into two parallel barrels

34 each of which supplies fuel to a plurality of engine cylinders.

The flow of air through airhorn 10 is controlled by a choke valve 16 mounted on a shaft 18 and provided with a spring pressed poppet valve 20 to permit a small amount of air to pass through airhorn 10 when the suction is great enough to compress spring 22. The choke valve may be manually controlled or may be automatically controlled by means such as those disclosed in S. F. Hunt Patent 2,031,709, issued February 25, 1936.

Fuel is supplied to the carburetor from float chamber 24, through a pair of fuel ducts 26 each of which terminates in a fuel discharge nozzle 28 positioned to discharge at the most restricted portion of a primary venturi 30 which in turn discharges at the most restricted portion of a secondary venturi 32. The venturis 30 and 32 are carried in middle body section 12 and are preferably formed integral therewith. The lower end of secondary venturi 32 is a slip fit in the upper portion of barrel 34 formed in the throttle body section 14. The flow of mixture through each of the carbureting passages thus formed by the three described sections is controlled by a throttle valve 36 mounted on a shaft 38 journalled in the walls of the throttle body section 14.

A flange 40 formed integral with the airhorn section 10 provides a cover for float chamber 24 and accommodates a needle valve 42 which when actuated by lever 44, fixed to float 46 and pivoted at 48, controls the flow of fuel into said float chamber and maintains a constant level therein. The upper portion of flange 40 has a recess which cooperates with a corresponding recess in the lower portion of a superposed tank section 50 to form a fuel reservoir 52 which receives fuel from chamber 54 through an outlet member 56 which is controlled by a gravity-actuated hinged valve member 106.

Chamber 54 accommodates a float 58 which is pivotally mounted by two arms 57 fixed to the float and pivoted to the lower ends of two downwardly extending studs 59. An arm 64 fixed to float 58 connects by means of a spring 66 with a shifting member 60 which has two parallel arms the lower ends of which are slotted and pivoted at 78 to the lower ends of two studs 67. A float actuated slide valve 68 is slidably mounted in studs 78 and operates to selectively admit atmospheric pressure to chamber 54 through a chamber 53 which communicates through an apertured felt pad 55, with the air cleaner 13. A second slide valve 62 operates to selectively cut off the vacuum in vacuum line 76 from chamber 54. Shifting member 60 connects with slide valves 68 and 62 in such a manner as to move the valves from one of their extreme positions to the other when the spring 66 is moved past the dead center, formed by a pin 78, by movement of float 58. As float 60

58 rises, arm 64 rises also, moving spring 66 past pin 78 and causing shifting member 60 to exert an upward force on slide valves 68 and 62 which will move the valve upwardly, thereby opening passage 70 and closing vacuum line 76 to allow air to enter chamber 54 from the air cleaner. The pressure existing in the upper portion of chamber 54 will immediately rise to atmospheric, and fuel will flow out of said chamber through outlet member 56. As the fuel level in chamber 54 drops, float 58 will rotate in a counterclockwise direction (Figures 2 and 3) around its pivot, thereby carrying arm 64 downwardly. As spring 66 passes the dead center at 78, it will cause lever 60 to rotate in the clockwise direction and exert a downward pull on slide valves 68 and 62, closing air inlet passage 70 and opening port 74 and vacuum line 76 leading to the suction venturis 80 and 82, which will exert suction in chamber 54 and draw fuel from supply tank 84 to chamber 54 through duct 86 while at the same time holding valve member 106 to its seat to prevent flow of fuel from chamber 54 to reservoir 52. A check valve 88 is positioned in fuel duct 86 to prevent fuel from flowing from chamber 54 back to the tank 84.

30 The auxiliary venturis 80 and 82 are positioned in series in the walls of the throttle body section 14. The primary venturi 80 discharges at the most restricted portion of the secondary venturi 82 which has inlets 83 and outlets 85 communicating with barrels 34 posterior to throttle valves 36. An unbalanced butterfly valve 94 is mounted on a shaft 96 in each barrel 34 between the inlets 83 and outlets 85 for the purpose of insuring a predetermined minimum suction in venturi 82, so that sufficient air will be forced to flow therethrough, even at wide open throttle, to lift fuel from storage tank 84 to chamber 54.

40 Each valve 94 is provided, at its greater portion, with a bent lip 95 provided with a lug 97 which holds the valve from fully closing. An adjustable coiled spring 99 yieldingly urges valves 94 to the closed position. This construction has been found to prevent fluttering, and the drag of lips 95 moves the valves to a very nearly open position when the engine is operating at high speed and open throttle. Fuel for idling purposes is supplied through the conventional idling passages 102 and 104.

50 A sleeve valve 89 is loosely mounted in an enlarged bore 87 formed in vacuum line 76, and is normally held in its uppermost position by a spring 91, in which position its notched upper end permits free flow of air past the valve. When the vacuum exceeds a predetermined value, however, it draws the valve 89 against the bottom of bore 87, so that the flow of air is restricted to an orifice 93 formed in a plug in the valve, as shown. This construction limits the maximum suction which can be applied to chamber 54, and thus prevents fuel in liquid or vapor form from being drawn through the line 76.

65 Figure 7 illustrates an arrangement wherein the suction venturis are disposed horizontally with their outlet posterior to a two-leaf spring pressed valve 100, a bypass 101 leading from the barrel 34 between the throttle valve 36 and valve 100 to the venturis. In this embodiment, the entrance to the 70 venturis is formed of a pressed steel conical member 105 preferably of $\frac{3}{4}$ " throat diameter and having an entrance angle of 20° , whereas the discharge angle of the venturi is 6° . The annular suction entrance 103 of the primary venturi is 75 preferably $\frac{1}{2}"$.

The operation of the device thus far described is as follows. It is apparent from the foregoing description that irrespective of the position of throttle valves 36 sufficient suction will at all times be present in the throat of primary venturi 80 to lift fuel from supply tank 84 to upper chamber 54. When the fuel lever in chamber 54 is at its highest point, represented by the line Y-Y in Figures 1 and 3, slide valve 68 will be in the position shown in Figures 2 and 3, in which position it permits air to enter through passage 70 to maintain the pressure in chamber 54 at atmospheric. The resulting head of fuel unseats valve member 106, permitting the fuel in chamber 54 to be discharged into reservoir 52 and thence into float chamber 24 at a rate controlled by needle valve 42. As the fuel level in chamber 54 lowers, float 58 moves spring 66 past the dead-center position represented by pin 78, whereupon shifting member 60 will move valves 68 and 62 downwardly, thereby closing atmospheric passage 70 and opening port 74 to permit the suction developed at venturi 80 to be transmitted to the chamber 54. The suction draws valve member 106 tightly to its seat, and draws fuel from the supply tank 84 to chamber 54, thus gradually raising the fuel level therein. Float 58 is moved upwardly by the rising fuel level, and when it approaches the position shown in Figures 2 and 3, the spring 66 will be moved upwardly past dead center 78, and will thus overcome the resistance of valves 68 and 62 and move them upwardly, thereby closing port 74 leading to the suction venturis and opening passage 70 to restore the pressure in chamber 54 to atmospheric. The 35 weight of the fuel being now augmented by atmospheric pressure, will thereupon force valve member 106 from its seat and the fuel will flow to reservoir 52, as before described, and the cycle 40 will then be repeated.

I claim:

1. In a device of the class described, a variable level fuel chamber, a source of fuel communicating with the chamber below the lowest fuel level thereof, a source of suction, passages connecting said chamber with said source of suction and with atmosphere, valves in said passages, a float pivotally mounted in said chamber, and mechanism connecting said float with said valves comprising an oscillating member pivoted at one end and having its free end connected to the valves, a movable member fixed to the float and movable to opposite sides of the pivot of said oscillating member, and a tension spring connecting the movable member to the free end of the oscillating member. 50

2. In a device of the class described: a variable level fuel chamber; a source of fuel communicating with the chamber; a source of suction; passages connecting said chamber with said source of suction and with atmosphere; parallel valves in said passages so designed that when both are moved in the same direction one will close and the other will open; a float pivotally mounted within said chamber and mechanism connecting said float with said valves comprising an oscillating member pivoted at one end and having its free end connected to the valves, an arm fixed to the float and projecting therefrom to the vicinity of the pivoted end of the oscillating member, and a tension spring connecting said arm to the free end of the oscillating member. 60
